SIDNEY Y. WHITE, OF NEW YORK, N. Y., ASSIGNOR, BY MESNE ASSIGNMENTS, TO
RADIO CORPORATION OF AMERICA, OF NEW YORK, N. Y., A CORPORATION OF
DELAWARE

ELECTRICAL DETECTOR-AMPLIFIER CIRCUITS

Application filed September 1, 1925. Serial No. 53,799.

While my invention relates generally to electrical detector-amplifier circuits, it refers particularly to three-electrode vacuum tubes employed in the dual capacity of detector 5 and regenerative amplifier.

An object of my invention is to adjust the variable circuits of a three-electrode vacuum tube detector-amplifier so that the degree of regeneration will remain constant, or vary 10 in a pre-determined way, throughout a wide range of frequencies as the circuits are varied.

Another object of my invention is to adjust the degree of regeneration so that the 15 system will strongly amplify by regeneration throughout a wide range of frequencies without breaking into oscillations when changing the circuits from one frequency to another; or, adjusting the system to be in 20 oscillation throughout a wide range of frequencies when changing from one frequency to another. The one adjustment will provide for the reception of modulated or damped high frequency currents without the 25 usual annoyance of oscillations in changing from one wave length to another. The other adjustment will provide for the reception of continuous waves by the heterodyne or beat method throughout a wide range of frequencies 30 without the annoyance of adjusting the system to be in the oscillating state for each changing of wave length.

A further object of my invention is to take full advantage of the selectivity that 35 may be had at any one of a wide range of frequencies through producing regenerative amplification by a controlled reaction in the plate or output circuit of a three-electrode vacuum tube.

40 In my co-pending application, Serial Number 49,521 of August 11, 1925, I have explained how the reaction in the plate circuit of a three-electrode vacuum tube may be maintained constant while energy is being 45 transferred over a wide range of frequencies to the input circuit of a succeeding vacuum tube.

50 My present invention relates to a three-electrode vacuum tube detector-amplifier or detector-oscillator from which the energy is

abstracted in the form of low frequency effects corresponding to the detected modulations in the high frequency signals or the beat tones of the heterodyne, in case continuous waves are received. 55

My invention will be best understood by reference to the accompanying drawing in which Fig. 1 shows my invention applied to a radio receiver, and Fig. 2 is an explanatory diagram. 60

In Fig. 1, X is an antenna connected to ground G through a condenser C₃ and an inductance L₁, and may or may not include a condenser C₁, depending upon the characteristics of the antenna. High frequency energy is delivered to the vacuum tube VT₁ through the resonant circuit L₂, C₂, and C₃, the coupling to the antenna being maintained constant, or varied in any pre-determined manner, with frequency through the combination inductive coupling between L₁ and L₂ and the capacity coupling C₃, all more fully explained in the co-pending application heretofore referred to. The vacuum tube VT₁ is arranged to act as a straight amplifier through having its grid connected to the negative side of the filament heating circuit. The amplified high frequency currents in the output circuit of vacuum tube VT₁ are transferred to the input circuit of the detector-amplifier, or detector-oscillator, VT₂ through the variable circuit L'₂, C'₂ and C'₃, the coupling being maintained constant, or varied in any pre-determined manner, through the combination of the inductive coupling between L'₁ and L'₂ and the capacity coupling C'₃, all as explained in my co-pending application previously referred to. The radio frequency choke L₃ provides a path for the 65 direct current supplied to the plate of vacuum tube VT₁. Vacuum tube VT₂ is arranged to act as a detector through having its grid connected to the positive side of the filament supply line, and through provision of the well-known grid leak-stopping condenser combination GL. 70

As explained in my co-pending application, there is an interelectrode path in three-electrode vacuum tubes such as VT₂, through which some of the amplified energy in the 75 80 85 90 95 100

output circuit escapes to the input circuit to reinforce the input circuit energy, and I have explained that the amount and phase of energy which escapes to the input circuit determines whether or not the system will act 5 as a regenerative amplifier, or as an oscillator.

I have also explained that the amount of energy that escapes to the input circuit depends upon the reaction of the output circuit 10 on the amplified energy. It is well-known that with the present day high amplification vacuum tubes the reaction due to attempting to tune the output circuit becomes so strong 15 long before the output circuit is in resonance that the system breaks into oscillations, and by the time near resonance is reached, the system is a powerful oscillator. This is more clearly explained in the diagram of Fig. 2, 20 in which the horizontal dimensions represent frequency of the signal current, and vertical dimensions represent reaction of the plate circuit to the selected current. Let it be assumed that the input circuit is tuned to and 25 receiving signals of a frequency f shown in Fig. 2 by the dotted line. Assume that the output circuit is free from resistance other than that inherent in the vacuum tube and necessary elements, and is capable of being 30 varied with the input circuit. The curve Y of the figure shows in a general way the reaction had in the output circuit as this circuit is varied. The dotted line bb shows in 35 a general way the value of the reaction in the output circuit necessary to throw the system into oscillations, points on the curve below the dotted line representing the degree 40 of regenerative amplification and points on the curve above the dotted line representing the intensity of oscillations. It is therefore seen that in the entire range between frequency f' and f'' the system is in the oscillating state and not useful for regenerative amplification. It will also be noted that at the 45 points a' and a'' , the border lines between regenerative amplification and oscillation, the curve is very steep, so that operating a vacuum tube near these points is an extremely critical and unstable condition. It is readily 50 apparent that, under the conditions outlined, no particular advantages are had in the matter of selectivity through tuning the output circuit to produce regenerative amplification.

55 The curve Y can be forced below the line bb into a form such as the dotted line curve Y' by introducing a substantial resistance in the output circuit. This procedure will result in a very much broadened curve as shown 60 which, as is readily obvious, offers no advantage in the matter of selectivity.

The object of my invention is to produce a sharply defined curve, such as Z shown in Fig. 2, which may be held below the critical 65 line bb throughout a wide range of frequen-

cies of modulated or damp wave signals, or may be slightly projected above the critical line bb and maintained there throughout a wide range of frequencies for reception of continuous wave signals.

I accomplish this result by coupling a circuit containing inductance L''_2 , variable capacity C''_2 and capacity C''_3 to the output circuit of VT2 through the inductive coupling between L''_1 and L''_2 and the capacity 70 coupling C''_3 .

I have explained in my co-pending application previously referred to how the capacity coupling decreases with increase of frequency, and how the inductive coupling 75 increases with increase of frequency, and how the combination may be adjusted to give a coupling that will remain constant throughout a wide range of frequencies; or, in other words, how this coupled, variable circuit may 80 be made to create a constant reaction through the internal path of vacuum tube VT2. It is readily apparent that by adjusting the degree or looseness of this coupling which remains constant it may be maintained below 85 or above the critical line bb . It will also be readily obvious to those skilled in the art 90 that the sharpness of the curve Z of Fig. 2 provides a condition of extreme selectivity 95 in the system I have outlined.

95 Telephones T are inserted in the path provided for the direct current supply to the plate of vacuum tube VT2 to convert the low frequency effects into sound, or these telephones may be substituted by a transformer T' , shown in dotted lines, leading to one or more stages of audio frequency amplification. If the telephones T , or transformer T' , have a distributed capacity in their windings too large to prevent high frequency 100 currents from freely passing, the path may be re-inforced against passage of high frequency currents by insertion of a suitable 105 radio frequency choke $L4$.

The lines marked $+A-B$, $-A$ and $+B$ 110 provide the usual system for heating the filaments of the vacuum tubes and energizing the plate circuits, and are thought to require no explanation.

115 While I have shown the system as including a vacuum tube VT1 for straight amplification, it is readily obvious that this tube may be omitted, in which event the system would be completed by connecting the antenna X in a suitable manner to the input circuit of vacuum tube VT2.

120 Although I have illustrated my invention in connection with a radio receiver, it is readily applicable to other forms of electrical communication, and I do not intend that it be limited to the system chosen for illustrative purposes.

Having fully described my invention, I claim:

1. The combination of a three-electrode 130

vacuum tube, a tunable high frequency input circuit, an output circuit, means operating said vacuum tube as a detector, a high frequency circuit, variable in consonance with said input circuit, means for coupling said high frequency circuit to said output circuit, the ratio of energy transfer of said coupling being substantially less than unity, said coupling being adjusted to remain substantially constant as said second circuit is varied, and means associated with said output circuit for abstracting detected energy therefrom.

2. The combination of a three-electrode vacuum tube, a tunable high frequency input circuit, an output circuit, means for impressing high frequency currents modulated at lower frequency on said input circuit, means operating said vacuum tube as a detector, a high frequency circuit variable in consonance with said input circuit coupled to said output circuit, means for maintaining the reaction of said variable circuit on said output circuit substantially constant with frequency, including means for maintaining the coupling between said output circuit and said variable circuit substantially less than unity as said variable circuit is varied, as said second circuit is varied, and means associated with said output circuit for abstracting energy of said lower frequency therefrom.

3. The combination of a three-electrode vacuum tube, a tunable high frequency input circuit, an output circuit, means operating said vacuum tube as a detector, a high frequency circuit variable in consonance with said input circuit, a coupling comprising capacitively and inductively reacting elements associating said variable circuit with said output circuit, said coupling being adjusted to remain substantially constant as said variable circuit is varied in consonance with said input circuit, and means associated with said output circuit for abstracting detected energy therefrom.

4. The combination of a three-electrode vacuum tube, a tunable high frequency input circuit, an output circuit, means for impressing high frequency energy modulated at lower frequency on said input circuit, means operating said vacuum tube as a detector, a high frequency circuit variable in consonance with said input circuit, a coupling comprising capacitively and inductively reacting elements associating said variable circuit with said output circuit, said coupling being adjusted to remain substantially constant as said variable circuit is varied in consonance with said input circuit, and means associated with said output circuit for abstracting energy of said lower frequency therefrom.

5. The combination of a three-electrode vacuum tube, a tunable high frequency input circuit, an output circuit, means operating said vacuum tube as a detector, a high frequency circuit variable in consonance with said input circuit, a combined capacitive and inductive coupling between said output and variable circuits, said coupling being adjusted to a predetermined degree of looseness and to remain substantially constant with frequency, and means associated with said output circuit for abstracting detected energy therefrom.

frequency circuit variable in consonance with said input circuit, a coupling comprising capacitively and inductively reacting elements, said elements transferring energy in phase accord from said output circuit, and means associated with said output circuit to said variable circuit for abstracting detected energy therefrom.

6. The combination of a three-electrode vacuum tube having a tunable high frequency input circuit and an output circuit, means operating said vacuum tube as a detector, a high frequency circuit variable in consonance with said input circuit coupled to said output circuit, means for maintaining the reaction of said variable circuit on said output circuit substantially constant with frequency including means for maintaining the coupling between said output circuit and variable circuit substantially constant as said variable circuit is varied, and means associated with said output circuit for abstracting detected energy therefrom.

7. The combination with a three-electrode vacuum tube having a tunable high frequency input circuit, an output circuit and means for operating said vacuum tube as a detector, of means for causing and controlling regeneration in said vacuum tube and circuits with variation of frequency comprising a high frequency circuit variable in consonance with said input circuit, a combined capacitive and inductive coupling between said output and variable circuits, said coupling being adjusted to a predetermined degree of looseness and to remain substantially constant with frequency, and means associated with said output circuit for abstracting detected energy therefrom.

8. The combination with a three-electrode vacuum tube having a tunable high frequency input circuit, an output circuit and means for operating said tube as a detector, of means for maintaining the régénérative reaction through the interelectrode capacity of said tube constant with frequency over a wide range of frequencies comprising a high frequency circuit variable in consonance with said input circuit loosely coupled to said output circuit, means for maintaining said coupling substantially constant as said coupled circuit is varied, and means associated with said output circuit for abstracting detected energy therefrom.

In testimony whereof I affix my signature. 120
